UNITED STATES PATENT OFFICE.

WILLIAM F. MINOR, OF NEW YORK, N. Y.

TIMER.

1,072,973.

Specification of Letters Patent. Patented Sept. 9, 1913.

Application filed November 7, 1912. Serial No. 729,998.

To all whom it may concern:

Be it known that I, WILLIAM F. MINOR, a citizen of the United States, and a resident of the city of New York, borough of 5 Manhattan, in the county and State of New York, have invented a new and Improved Timer, of which the following is a full, clear, and exact description.

This invention relates to improvements 10 in timing devices, and has for an object to provide an improved structure designed to be set so as to cause the operation of a signal at certain spaced intervals, and in a certain way.

15 A further object of the invention is to provide a timing device adapted to be used in sports and contests of various kinds where a limited time is allowed for the preparation, and a limited time is allowed for 20 the execution or for the contest, the device automatically measuring off these respective times in succession and thereby obviating any charge that the judge of the events may not be fair or correct in his timing of 25 the contestants.

A further object of the invention more specifically is the provision of an improved construction of contacts and signal devices associated with a clock mechanism, whereby 30 the clock mechanism will cause the contacts which control the signal devices to be opened and closed at certain intervals regularly without the intervention or assistance of an operator.

35 In carrying out the objects of the invention, a suitable housing of any desired kind is provided, in which a clock mechanism is mounted. Connected with the clock mechanism are a plurality of switches or contact 40 members operated in certain predetermined relationship to each other, the operating parts being connected with the clock mechanism and driven thereby at a certain speed. Connected with these switches or contact 45 members are a plurality of signal devices which are operated when the switches or contacts are closed. As the contacts are operated by means connected with the clock mechanism it will be seen that the signals will be operated at certain spaced intervals and for a 50 certain length of time as long as the clock mechanism is in working order. In addition to this automatic working mechanism, a manually operated switch is provided for 55 throwing an electrical switch into connec-

tion with the clock mechanism so that the signal connected therewith may be operated a certain number of times according to the length of time the manually operated switch structure is set or being held in a predetermined position. This last mentioned switch and associated parts is designed to cause a proper operation of a counting signal adapted to operate at certain intervals, as for instance once each second. When 60 the manually operated switch is moved or depressed, the electric switch associated therewith is immediately operated by the clock mechanism for causing the counting signal to operate and this electrical switch is 65 operated successively each second as long as the manually operated switch is depressed so that any desired number of seconds may be signaled or counted off.

A practical embodiment of the invention 70 is represented in the accompanying drawings forming a part of this specification, in which similar characters of reference indicate corresponding parts in all the views.

Figure 1 is a perspective view of an embodiment of the invention, the housing being shown open and the device ready for operation; Fig. 2 is a longitudinal vertical section through the clock mechanism shown in Fig. 1, and associated parts; Fig. 3 is a 85 section through Fig. 2 approximately on the line 3—3; and Fig. 4 is a diagrammatic view of the wiring, signal mechanism, electrical switches, and associated parts of the structure shown in Fig. 1.

In the construction of the device embodying the invention it is aimed to provide a signal device to be used for sports and in games of various kinds where certain events are adapted to be timed. In carrying 90 out this idea, a signal gong or bell is provided designed to be sounded or rung an appreciable time just immediately before starting a contest, and also the same gong is adapted to be rung or sounded immediately at the close of the contest. In order to allow the contestants to get ready, a signal device, preferably a buzzer, is provided adapted to operate a certain time before a gong is sounded, as for instance ten 100 seconds. This will give the contestants time to get in position so as to start immediately the gong begins to sound. Under some circumstances it is desired to mark off a comparatively short period of time and to 110

indicate the number of seconds a particular event requires. In order to provide a device for accomplishing this purpose, a magnetically operated hammer is provided, designed to strike the signal gong successively at stated intervals. This counting device is caused to be operated by suitable mechanism associated with a clock so that the hammer will strike at certain intervals.

10 However, in order to cause the hammer to count only when desired, a manually operated switch is associated with the connections arranged adjacent the clock, this manually operated switch mechanism controlling the connections in order that the counting device will only operate when the manually operated switch is moved to a certain position and held in that position.

15 Referring to the accompanying drawings by numerals, 1 indicates a housing of any desired kind, in which the mechanism embodying the invention is mounted. Arranged in the housing 1 is a clock mechanism 2 of any desired construction. Associated with the clock mechanism 2 and arranged preferably in the lid 3, are a plurality of signal devices, namely a gong and counting signal 5, and a buzzer 6. The detail constructions of these mechanism or devices are of any usual or preferred kind and operate in the ordinary manner, so that no additional description thereof will be necessary. These devices are connected to the respective binding posts 7, 8, 9, 10, 11, 12, and 13, arranged at one end of the housing 1, and the binding posts are connected to various switch mechanisms hereinafter fully described, and also a battery, as more clearly shown in Fig. 4. Referring more particularly to Fig. 4, 13 and 14 indicate feed wires connected to any suitable electrical supply, these wires being connected to binding posts 15 and 16, mounted at any suitable point on the housing 1. The binding post 15 is connected through wire 17 to one contact of switch 18, and the other contact of the switch 18 is connected to binding post 8 through wire 19. The binding posts 7 and 8 are connected to the opposite sides of the gong structure 4 so that when current is impressed on its binding posts the gong 4 will be actuated. Binding post 7 has connected therewith wire 20, which is connected to a contact 21, preferably a resilient contact, which is adapted to engage successively the projections 23 and 24 on a rotary member 25. The rotary member 25 is rigidly secured to an axle 26, to which also a rotary member 27 is rigidly secured, provided with extensions 28 and 29 arranged in almost axial alinement with the extensions 23 and 24. The members 25 and 27, and also the shaft 26 are formed of metal and are therefore grounded on the frame 30 of the clock 2. By this construc-

tion and arrangement when current passes from binding post 7 through wire 20, the same will pass through contact 22 and from thence through projections 23 or 24 if the same are touching with member 22, and from thence to the frame 30. Binding post 16 is grounded to wire 31 on frame 30 so that the circuit is complete for gong 4 whenever the contact member 22 is in engagement with the projections 23 or 24. The member 25 carrying projections 23 and 24, is designed to rotate at any desired speed. Presuming that the member 25 will rotate once every four minutes, the time that the contact 23 is in engagement with either of the projections 23 or 24 will be short, probably not more than six to eight seconds. The projections 23 and 24 may be set any desired distance apart, as for instance at a 90° angle. Assuming that the member 25 rotates once in every four minutes, this will cause an interval of one minute between the sounding of the gong 4, and then an interval of three minutes, followed by an interval of one minute, which in turn is followed by an interval of three minutes, and so on, as long as switch 18 is closed and clock 2 is operating. In locating the member 27 on the shaft 26, the projections 28 and 29 are set slightly out of alinement with the projections 23 and 24 so as to engage contact 32 a short time before either of the projections 23 or 24 engage contact 22, in order that a preliminary signal will be sounded. Preferably the contact 28 on member 27 is set so as to move out of engagement with the contact 32 substantially simultaneously with the engagement of contact 22 with projection 23, the shaft 26 and members carried thereby moving in the direction of the arrow shown in Fig. 4. When contact 32 is in engagement with either of the projections 28 or 29, current will flow from binding post 15, through wire 33 to one of the binding posts of switch 34. From switch 34 the current will pass through wire 35, to binding post 12, and from binding post 12 to buzzer 6, back to binding post 11. From binding post 11 current will pass over wire 26 to contact 32, either of the projections 28 or 29 according to which is in engagement with contact 32, shaft 26, frame 30, wire 31, and from thence to the source of power, to binding post 16. From this construction and arrangement it will be seen that the buzzer 6 will cause a preliminary signal to be sounded when contact 32 engages the extension 29, and as soon as this preliminary signal has ceased, the gong 4 will sound as the circuit therefor has been closed by the contact 22 engaging extension 24. As shaft 26 rotates, the contact will be broken between members 22 and 32, and projections 29 and 24. If shaft 26 is rotating at the rate of once every four minutes,

there will be a one minute interval, and then the buzzer 6 will sound for a short time, after which gong 4 will sound for about the same time. After gong 4 has 5 sounded, contact 22 will have passed the extension 23 and the signal mechanism will not operate again for a space of three minutes, or until contact 32 engages extension 29. It will be evident that the shaft 26 10 could be made to rotate faster or slower, as desired, and the extensions 28 and 29, and also the extensions 23 and 24, could be arranged either closer together or farther apart, without departing from the spirit of 15 the invention.

When it is desired to count off any desired 20 number of seconds, or any other desired number of spaced intervals, a third device is caused to operate, namely the counting device 5. In order to operate this counting device, a thumb member 37 (Fig. 2) is depressed, which will move pivotally a spring-pressed lever 38. The lever 38 is normally held in a predetermined position by a spring 25 39 so that the end 40 will normally be in the path of movement of the pin 41 which is rigidly secured to gear wheel 42. The gear wheel 42 carries a squirrel cage pinion 43 meshing with the gear wheel 44. The gear wheel 44 carries a plurality of spaced stops 30 45 which act in the capacity of contact members for contacting with a resilient contact 46 (Fig. 3).

When the member 37 is depressed it will 35 raise end 40 of lever 38 as lever 38 is pivotally mounted at 47 to frame 30 so that the end 40 will be elevated or moved out of the path of movement of the stop 41. This will leave gear wheel 42 free to rotate under the 40 action of a driving spring 48. The driving spring 48 has one end connected with the frame 30 and the opposite end connected with shaft 49, which shaft in turn is rigidly secured to a gear wheel 50. The gear wheel 45 50 meshes with a squirrel cage pinion 51 secured to shaft 52. The gear wheel 44 is also rigidly secured to shaft 52 so that whenever spring 48 is permitted to operate, the wheel 44 will be rotated. The wheel 44 meshes 55 with pinion 43, which pinion is rigidly secured to a shaft carrying gear wheel 43', which gear wheel meshes with pinion 52', which pinion is rigidly secured to shaft carrying the gear wheel 42. Gear wheel 42 meshes with pinion 53, which is rigidly secured to shaft 54, to which is connected a fan or air brake 55. By this system or train 60 of gearing the rotation of gear wheel 44 under the action of spring 48 is controlled by the fan or air brake 55 so that gear wheel 44 will move at a certain speed, as for instance the distance between two adjacent stops 45 during the space of one second. If this gear wheel 44 is rotated at this rate, 65 contact 46 will strike or engage one of the

stops 45 each second, and thus complete a circuit once each second. The wheels 44, 43' and 42 are so intergeared that wheel 42 will rotate several times while wheel 43' is rotating once, and wheel 43' will in turn rotate 70 several times while wheel 44 is rotating once. In this way the stop 41 passes end 40 of lever 38 several times during the passage of one of the stops 45 on wheel 44 from one side of member 46 to the other so that 75 whenever end 40 is permitted to engage stop 41, wheel 44 is stopped almost instantly from rotation. Referring to Fig. 4, when any one of the stops 45 is in engagement with contact 46, current will flow from binding post 15, over wire 56, to binding post 9, and from thence through the counting mechanism 5 to binding post 10. From binding post 10 the current will flow to wire 57, to contact 46, to stop 45, wheel 44, frame 80 85 30, wire 31; and from thence through binding post 16, and wire 14 to the source of supply. The current passing through this circuit will energize the magnets of counting signal 5 and cause the hammer thereof to 90 strike the bell or gong 4 once. The current will flow only during the time the contact 46 is engaging with stop 45, and the circuit will be broken as soon as disengaged. The counter 5 is substantially of the ordinary bell 95 structure without an independent gong, as clearly shown in Fig. 4. However, it might be stated that the same is formed with an electro magnet connected with binding posts 9 and 10 so as to attract a pivotally mounted 100 armature to which is rigidly connected a hammer. When current is caused to pass through the coils of the electro magnet in counter 5, the same will cause the hammer thereof to strike gong 4 once, but will allow 105 no further movement of the hammer, as there is no make and break provided in the counter. As soon as the circuit to the magnet in counter 5 is broken and then reestablished, the hammer of the counter will again 110 strike gong 4. As long as thumb member 37 is held depressed, wheel 42 will remain free to rotate and consequently spring 48 will cause a continuous rotation of wheel 44 so that the stops 45 may successively engage 115 contact 46. Upon each engagement of stops 45 with contact 46, current will pass through the circuit just traced and cause one stroke of the hammer of member 5 upon each engagement of contact 46 with the stops 45. 120 Assuming that the stops 45 engage contact 46 at intervals of one second apart, the bell or gong 4 will be sounded at the same interval and will continue to sound at this interval as long as the thumb member 37 is held 125 depressed. When the thumb member 37 is released, lever 38 will be moved pivotally by spring 39 so that the end 40 will move into the path of movement of stop 41 and thus prevent the rotation of wheel 42 and 130

the train of gearing associated therewith, including wheel 44. The train of gearing of which gear wheel 44 is a part is driven by spring 48 (Fig. 2) and this spring and the 5 train of gearing driven thereby is not in any way connected with the clock mechanism, which mechanism is of any usual preferred type. The members 25 and 27, shown in Figs. 2 and 4, are the only ones operated by the clock mechanism and the same are 10 operated continuously. The connections between the clock mechanism 2 and shaft 26 carrying members 25 and 27, are illustrated herewith. Referring more particularly to 15 these figures, 56 is a hand or pointer secured to shaft 26 and arranged so as to appear on the face of the clock. A suitable dial may be provided over which the hand or pointer 56 will be adapted to move. Shaft 26 has 20 rigidly secured thereto a pinion 57 which meshes with gear wheel 58. The gear wheel 58 is rigidly secured to a suitable shaft 59, which has also rigidly secured thereto a pinion 60. This pinion meshes with a gear 25 wheel 61 secured to the usual shaft 62 carrying the usual minute hand 63. When shaft 26 is designed to rotate once every four minutes, the gear wheels 61 and 58, and the pinions 57 and 60, are arranged of the 30 proper size for providing the proper ratio between shaft 62 and shaft 26. When the shaft 26 is adapted to rotate faster or slower, the connecting gearing is changed accordingly. This change of gears may be 35 made without departing from the spirit of the invention.

The particular construction of clock mechanism does not form any part of the present invention, as any desired clock 40 mechanism may be used without departing from the spirit of the invention so that only certain of the mechanism has been shown to illustrate the invention.

Having thus described my invention, I 45 claim as new and desire to secure by Letters Patent:—

1. In a device of the character described, a pair of electrically operated signal devices, a clock mechanism, a circuit for each 50 of said signal devices, and means operated by said clock mechanism for opening and closing said circuits, said means including a contact member for each of the circuits, and a wheel for each of said contact members, 55 said wheels being operated by said clock mechanism at a predetermined speed and each of the wheels being formed with spaced projections, the projections of one of said wheels being arranged in advance of the 60 projection on the other wheel whereby said signal devices are caused to operate in succession and at certain spaced intervals of time.

2. In a device of the character described, 65 a main signal, a preliminary signal, a cir-

cuit for each of said signals, a switch interposed in each of said circuits, each of said switches comprising a stationary contact member and a rotating contact member, the rotating contact members of said switches 70 having projections designed to be moved into engagement with said stationary contact members, said projections being set so as to engage said stationary contact members at different times whereby said preliminary signal will be operated at one time and said main signal at another time, a clock mechanism, and means connecting said clock mechanism with said rotating contact members whereby the projections on said 75 rotating contact members will engage said stationary contact members at certain intervals of time and will remain in engagement with said contact members for part of their revolution for causing the signals to 80 operate a predetermined length of time and for causing a predetermined length of time 85 to elapse between each operation of said signal devices.

3. In a device of the character described, 90 a principal signal device, an auxiliary signal device, a circuit for each of said signal devices, a switch interposed in each of said circuits, each of said switches comprising a substantially stationary contact member and 95 a rotatable contact member, said rotatable contact member being formed with a rotating shaft and a pair of disks having a plurality of spaced projections extending therefrom adapted to engage said stationary contacts during the rotation of said shaft whereby said circuits are closed for a predetermined length of time upon the engagement of said projections with said stationary contacts and said circuits will be open 100 for a predetermined length of time according to the distance between said projections and the speed of rotation of said shaft, a clock mechanism, and means for connecting said shaft with said clock mechanism so as 110 to rotate the same at a certain speed.

4. In a device of the character described, a principal signal device, a preliminary signal device, and a counting signal device, an electrical circuit for each of said signal devices, a switch interposed in the circuit of 115 said principal signal device and said preliminary signal device, a clockwork, means for connecting said clockwork with said switches for causing the same to open and close the circuits of said principal signal device and said preliminary signal device at certain intervals, a switch arranged in the circuit of said counting signal device, said last mentioned switch comprising a stationary member, a rotating wheel arranged adjacent 120 said stationary member formed with spaced projections adapted to engage said stationary member at certain intervals as 125 the wheel rotates, means for driving said 130

wheel, and means for regulating the speed at which said wheel is rotated whereby the circuit of said counting signal device is regularly opened and closed at certain stated 5 intervals, and manually operated means for locking said wheel against rotation.

5. In a device of the character described, an electrically operated counting signal, a circuit for said counting signal, a switch 10 interposed in said circuit comprising a flexible fixed member, a rotatable wheel and a plurality of spaced pins mounted on said wheel and arranged so as to strike against said flexible fixed member whereby the circuit 15 of said counting signal is closed at spaced intervals according to the speed of said wheel, a train of gearing connected with said wheel, power means connected with said train of gearing for operating the 20 same and a brake mechanism connected with said train of gearing for regulating the speed of said wheel whereby said projections will engage said flexible fixed member at certain stated intervals, and a pivotally 25 mounted manually operated stop adapted to engage one of the gears of said train of

gearing for locking the train of gearing against movement.

6. In a device of the character described, a principal signal, an electrical circuit therefor, an electrically operated preliminary signal, an electrical circuit therefor, an electrically operated counting signal, an electrical circuit therefor, a switch for each of said circuits, a clock mechanism, means 30 for connecting the clock mechanism with the switches in said principal signal and said preliminary signal whereby said last mentioned signals are operated at certain times and for certain lengths of time, a 35 switch mechanism interposed in the circuit of said counting signal, means for opening and closing said last mentioned switch, and a lock for locking said last mentioned switch against movement. 40

In testimony whereof I have signed my name to this specification in the presence of two subscribing witnesses.
